UNITED STATES PATENT OFFICE

2,607,102

LATCH CONSTRUCTION FOR SEALED
BURIAL CASKET

Bernard J. Slaughter, Jr., Cincinnati, Ohio, assignor to The Crane & Breed Casket Company, Cincinnati, Ohio, a corporation of Ohio

Application January 4, 1950, Serial No. 136,731

1 Claim. (Cl. 27—17)

1

This invention relates to a latch construction for a sealed burial casket and more particularly relates to a construction for a sealed latch which is adapted for drawing a casket lid down on a casket body.

The latch is generally of the type shown in the copending application of Bernard J. Slaughter, Jr. and Raymond F. Brown, Serial No. 695,136 filed September 6, 1946, now Patent No. 2,506,553 dated May 2, 1950. The latch is for use in a casket of the type having a peripheral compressible gasket held between the casket lid and the open-topped body of the casket. The lid and the casket body each have a hollow rim, the rims having relatively broad, flat opposed faces. The rim of the casket body is provided with a peripheral trough in which a circumferential gasket is retained. The lid compresses the gasket in the trough when the lid is closed. A plurality of latch keepers attached to one of the rims are engaged by latches which are attached to the other rim.

An object of this invention is to provide a latch construction in which the latch engages a latch keeper which is mounted inboard of the gasket so that no auxiliary gaskets are required to seal the opening through which the latch keeper extends when the lid is closed.

A further object of this invention is to provide a latch construction for a casket of this type in which the latch includes a shaft which extends across the rim and passes inboard of the gasket so that a latch operating plate mounted on the shaft can engage the latch keeper inboard of the gasket.

A further object of this invention is to provide a latch construction for a casket of this type in which the latch is elongated and is rigidly supported at both ends.

Briefly this invention provides a latch which includes an elongated sleeve which is attached to and extends through the rim of a hollow open-topped casket body. A shaft is rotatable in the sleeve. The head of the shaft is enlarged and is accessible exteriorly of the casket so that the shaft can be turned from outside of the casket. A resilient substantially impervious washer mounted on the shaft under the head of the shaft forms a seal between the sleeve and the shaft. The elongated sleeve and shaft extend inboard of the gasket, and a latch plate is non-rotatably attached to the shaft inboard of the gasket. A latch keeper is attached to the rim of the casket lid inboard of the gasket, and the latch plate is adapted to engage the latch keeper to draw the rim of the lid down upon the rim of the casket

body. Since the latch keeper and latch plate are mounted inboard of the peripheral gasket, no auxiliary gasketing is required on the latch keeper and latch plate. The shaft further extends beyond the sleeve into a bearing opening in a member which is attached to the rim of the casket body inboard of the latch member for supporting the shaft at its inner end.

The above and other objects and features of the invention will in part be apparent, and will in part be obvious from the following detailed description and the drawings, in which:

Fig. 1 is a view in side elevation showing a casket generally, the casket being constructed in accordance with an embodiment of this invention;

Fig. 2 is a fragmentary sectional view taken along a line II—II in Fig. 1;

Fig. 3 is an enlarged transverse sectional view showing details of a latch member;

Fig. 4 is a sectional view taken along a line IV—IV in Fig. 3;

Fig. 5 is a view in side elevation showing a trunnion bearing member and a support therefor; and

Fig. 6 is a fragmentary view in lengthwise vertical section showing an end of the casket.

In the following detailed description and the drawings, like reference characters indicate like parts.

In Figure 1 a casket is shown which includes a hollow open-topped casket body 10 and lid sections 12 and 13. As shown in Fig. 2, the lid sections are hinged along a lengthwise side of the casket body, as indicated at 13'. A compressible peripheral gasket 14 extends completely around the casket to form a seal between the body 11 and the lid sections 12 and 13 when the lid sections are closed. In addition, an appropriate transverse gasket, not shown in detail, may be provided between the lid sections 12 and 13. The gasket 14 may be of the type generally described in the co-pending applications Serial No. 631,924 filed November 30, 1945, of B. J. Slaughter, Jr., and Lawrence Gerold, now abandoned, and Serial No. 714,384 filed December 6, 1949, of B. J. Slaughter, Jr., and Raymond W. Brown, now Patent No. 2,524,402 dated October 3, 1950. The gasket 14 is held in a trough 16 in the rim of the casket body. The trough is slightly larger than the gasket so that when the lid sections are lowered, as indicated in Fig. 2, the gasket 14 is completely held within the trough 16 and the weight of the lid is carried by a substantially metal-to-metal contact between the rim of the

casket body and the rim of the casket lid. The tubular gasket shown is a preferred type of gasket. However, it is to be understood that other types of gaskets, for example solid or flat gaskets may be substituted for the tubular gasket shown.

As shown in Fig. 1, a series of latches 16' are provided along the length of the casket for drawing the rims together. Two latches are provided along the front of each lid section, as shown in Fig. 1 and, in addition, a latch is provided at the end of each lid section as shown in Fig. 6. Only one of the latches will be described in detail as all latches are similar in construction.

As shown in Fig. 3, the gasket holding trough 16 is disposed adjacent the outer edge of a rim face 17. Inboard of the trough 16, the rim face 17 is apertured, as indicated at 18. A latch keeper 19 is attached to a rim face 21 of the lid and is adapted to extend through the aperture 18 when the lid is closed.

A latch supporting sleeve 22 extends through an aperture in the rim of the casket body. The sleeve 22 is elongated and extends beneath the gasket holding trough 16. A head 23 on the sleeve 22 is enlarged and is disposed outside the casket. The sleeve extends through an opening in the casket side wall 26. A resilient annular gasket 24 fits around the sleeve 22 inside the casket body and is held against the side wall by a nut 27 threaded on the sleeve 22. The nut holds the gasket 24 against the wall 26 and the sleeve 22 to form a seal therebetween.

A shaft 28 is rotatable in the bore of the sleeve 22. The outer end of the sleeve is counterbored to form a recess 29 for receiving an enlarged head 30 of the shaft. The shaft 28 is provided with a neck 31 of reduced diameter immediately inboard of the head 30 in which is disposed a small annular impervious resilient washer 32. The washer 32 provides a seal between the shaft 28 and the sleeve 22. A slot 33 in the head of the shaft is exposed outside the rim of the casket body and can receive the blade of a screw driver for turning the shaft.

The inner end of the shaft 28 extends inboard of the sleeve 22 and is provided with a flat-sided section 34 upon which is mounted a latch plate 35 which rotates with the shaft 28. As shown in Fig. 4, the latch plate 35 includes an inner portion having a central opening for receiving the flat-sided portion 34 of the shaft, a radial arm 36, and a horn 37 extending from the outer end of the radial arm 36. The horn 37 is provided with a cam edge 38 (Fig. 4), spaced points on which are disposed at progressively shorter distances from the axis of the shaft in the direction of the radial arm so that when the horn engages the latch keeper 19, the horn draws the lid downwardly against the rim of the casket body.

A nut 39 threaded to the shaft 28 holds the latch plate in position thereon. The shaft 28 extends inboard of the nut 39 to form a trunnion portion 41. The trunnion 41 extends into a bearing opening 42 (Fig. 5) in a trunnion supporting member 43. Member 43 in turn is attached inside a depending flange 44 which forms a portion of the rim of the casket body inboard of the latch keeper and latch plate.

Since the latch keeper and latch plate are disposed inboard of the gasket 24, there is no necessity for auxiliary gaskets surrounding the latch keeper and latch plate, for the gasket 24 provides

a seal which is disposed outboard of the latch keeper and the latch plate. The trunnion supporting member, provides a stable support for the inner end of the shaft 28. The outer end of the shaft 28 is supported in the aperture of the rim side wall 26 so that both ends of the shaft 28 are firmly yet rotatably supported.

The device described herein and illustrated in the drawings is subject to structural modification without departing from the spirit and scope of the appended claim.

Having described my invention what I claim as new and desire to secure by Letters Patent is:

In a sealer casket having an open-topped body portion and a lid hinged to said body portion and adapted to close the top of said body portion, the lid and the body portion each having a hollow rim substantially rectangular in section, top and bottom faces of the respective body and lid rims 15 engaging each other when the lid is closed, the engaging face of one of said rims having a gasket holding trough extending circumferentially thereof, and a compressible gasket in said trough adapted to form a seal between the body of the 20 casket and the lid when the casket is closed; the invention which comprises a latch keeper attached to the bottom face of the lid rim and extending downwardly therefrom, the top face of the body rim, inboard of the trough, having an 25 opening through which said latch keeper extends when the lid is closed, and a latch comprising a 30 sleeve extending through an opening in the outer side of the casket body rim and below the gasket trough, said sleeve having an enlarged head at 35 its outer end engaging the outer side of the casket body rim, a nut threaded on said sleeve inside the casket body rim, a resilient impervious washer held between said nut and the inner face of said 40 outer rim side of the casket body rim to seal said opening, the head of said sleeve being counterbored, a shaft extending through and rotatably mounted in said sleeve, said shaft having an enlarged head received in the counterbore of said 45 sleeve head, a resilient impervious washer under the head of the shaft forming a seal between the shaft and the sleeve, the inner end of the shaft extending inboard of the inner end of the sleeve, a latch member non-rotatably mounted on the 50 shaft inboard of the inner end of the sleeve, said latch member having a horn engageable with the latch keeper to draw the keeper toward the axis of the shaft to hold the rims together, the inner end of said shaft having a journal portion located inboard of the latch member, and a journal bearing member attached to the inside wall of the 55 casket body rim inboard of the latch member, said journal portion extending into the bearing of said journal bearing member to support the inner end of said shaft.

BERNARD J. SLAUGHTER, JR.
